UNITED STATES PATENT OFFICE

150,162

DESIGN FOR A DISPLAY DEVICE

Howard Scaman, Chicago, Ill.

Application July 31, 1946, Serial No. 132,120

Term of patent 3½ years

(Cl. D80—9)

To all whom it may concern:

Be it known that I, Howard Scaman, a citizen of the United States, residing at Chicago, in the county of Cook and State of Illinois, have invented a new, original, and ornamental Design for a Display Device, of which the following is a specification, reference being had to the accompanying drawing, forming a part thereof.

Fig. 1 is a perspective view of a display device embodying my novel design;

Fig. 2 is a front elevational view thereof; and
Fig. 3 is a top plan view thereof.

I claim:

The ornamental design for a display device, as shown.

HOWARD SCAMAN.
